STRAIGHTEDGE

Alan C. Ferguson and Arthur J. La Croix, Southbridge, Mass., assignors to Hyde Manufacturing Company, Southbridge, Mass., a corporation of Massachusetts

Application January 5, 1949, Serial No. 62

Term of patent 14 years

(Cl. D52—1)

To all whom it may concern:

Be it known that we, Alan C. Ferguson and Arthur J. La Croix, citizens of the United States, residing at Southbridge, in the county of Worcester and State of Massachusetts, have invented a new, original, and ornamental Design for Straightedge, of which the following is a specification, reference being had to the accompanying drawing, forming part thereof.

Fig. 1 is a perspective view of a straightedge, showing our new design.

Fig. 2 is an end elevation thereof.

We claim:

The ornamental design for a straightedge, as shown.

ALAN C. FERGUSON.
ARTHUR J. LA CROIX.
